FRITZ LOWENSTEIN, DECEASED, ASSIGNOR, BY MESNE ASSIGNMENTS, TO RADIO
PATENTS CORPORATION, A DOMESTIC CORPORATION.

APPARATUS FOR GENERATING ALTERNATING CURRENT.

Application filed November 29, 1918. Serial No. 264,645.

This invention relates to apparatus for generating alternating current, and more particularly to oscillation generating systems in which a source of direct current is utilized as the source of energy from which the alternating current is produced.

I am aware that various types of systems have been proposed heretofore for deriving alternating current from direct current, but such systems have not proved satisfactory in all respects. Some are complex, comparatively inefficient, and incapable of sufficiently accurate control, while others are incapable of a large power output.

It is, therefore, a principal object of my invention to provide apparatus for generating electrical oscillations, by means of which a high efficiency and accurate control may be attained in a simple manner with a comparatively large power out-put. Other objects of the invention will appear as the description of the invention proceeds.

In one practical form of system embodying my invention, direct current is supplied to a divided circuit consisting of a plurality of parallel branches, two in a typical instance, each of which includes a conductive gap and alternating potential-impressing means cooperating therewith. Thus, for example, each parallel branch may include an evacuated vessel of the audion type containing a heated filament cathode, a plate or wing anode, and a grid interposed in the conductive gap between the cathode and anode. The grids of the audions in the parallel branch circuits are electrically connected together, this grid circuit being electrically interlinked with a frequency-controlling or "steering" circuit, which is also electrically interlinked with both of the wing circuits. The steering circuit may be a circuit specially provided for the purpose; or the output circuit may be arranged to exercise also the functions of a steering circuit, as will hereinafter more fully appear. In any case, it is essential to the present invention that the steering circuit, whether it be an output circuit or a special auxiliary circuit, shall be capable of sharp tuning. In other words, the oscillation decrement of the steering circuit should always be less, and most desirably very much less, than is possible with a circuit containing an iron core, such as repeater circuit of the well known type, where

the oscillation decrement is commonly not less than 0.1. In the practice of the present invention, the oscillation decrement of the steering circuit is never as high as that of an iron core or repeater circuit; and in the best embodiments of the invention said decrement is of a much lower order of magnitude, say 0.01 or 0.001, in typical examples. By means of such a sharply tunable steering circuit, great accuracy in controlling the frequency of the alternating current generated, is attained, as well as other advantages, especially in high frequency work. When a system of the character described is in operation more current from the direct current source flows alternately through one wing circuit and then through the other, owing to the modulating effect of the interposed grids; and the relation of the wing circuits to the output circuit is such that an alternating current is thereby induced in the latter. The frequency of this alternating current is determined and governed with extreme accuracy by the sharply tuned steering circuit before mentioned which impresses upon the grid circuit whatever frequency may be desired, thereby causing an alternating rise and fall of potential in the respective grids in such manner that when the potential of one grid is raised, the other is lowered, and vice versa. Thus the modulating effect of the grids, which is electrostatic in the present invention, is positively governed and the output frequency accurately controlled in a regulable manner. The frequency may of course be adjusted or varied by suitable adjustment of the constants of the steering circuit, whether the latter be the output circuit proper or a special auxiliary circuit.

The objects and novel features of my invention will be more fully understood from the following description taken in connection with the drawing in which,—

Figs. 1 and 2 are diagrams of systems embodying my invention.

In the specific embodiments of my invention illustrated in the figures of the drawing, the divided circuit consists of two parallel branches or wing circuits X and Y, to which a battery B, or other suitable source of direct current, is connected by the conductors 10 and 11. The battery B together with the conductors 10 and 11 and the wing circuits

X and Y thus form a closed direct current input circuit for the generating system.

Vacuum tubes T and T', which, for example, may be audion tubes of well known construction, are connected in the branch circuits X and Y, respectively, the filaments 12 and 13 thereof being connected by conductors 14 and 15, respectively, to the conductor 10, and being heated by current from the batteries A and A', respectively, or by current from some other suitable source. The wings or anode plates 16 and 17, cooperating with the filaments 12 and 13, respectively, to form parallel conductive gaps, are connected by conductors 18 and 19 to the conductor 11.

The grids 20 and 21, constituting alternating potential impressing means, are interposed in the conductive gap between the filaments and plates of the tubes T and T', respectively. These grids extend across the streams of electrons passing from the respective filaments 12 and 13 to the plates 16 and 17, and when the respective potentials of the grids are varied, as by alternate increase and decrease, the currents flowing in circuits X and Y are modulated, by the electrostatic effect of the grids, so as to alternately increase and decrease the flow of current in the respective wing circuits. The grids 20 and 21 are electrically connected together by a conductor 22 that includes a winding 23, by means of which the potentials on the grids may be accurately controlled or varied, in a manner to be set forth later.

Most desirably an intermediate point, usually the mid-point of the winding 23, is connected as by lead 23^a to a point which may be either at substantially the same potential as the cathodes 12 and 13, or more negative than said cathodes, depending upon the use to which the system is to be put. To provide for operating under either condition, the lead 23^a is arranged for adjustable connection at 23^b either to conductor 10, for example, or to some point on the battery B' as in the particular arrangement illustrated. In the latter case, which is a condition best adapted for telephone work, a potential more negative than that of the cathodes 12 and 13, is impressed upon the grids 20 and 21, and the degree of this ultranegative potential may evidently be adjusted as desired by shifting the lead connection. For high frequency work, the connection may be shifted to equalize the grid and filament potentials.

The output or load circuit may comprise any suitable form of energy absorbing or translating means. As a specific example, the load circuit illustrated is a tuned antenna circuit for a wireless telegraph or telephone transmitter. The antenna circuit embodies an aerial 24, a ground 25, and inductances 26 and 27, which are inductively related, respec-

tively, to inductances 28 and 29 constituting portions of the conductors 18 and 19 of the wing circuits X and Y, respectively, the antenna circuit being thereby loosely coupled to both said wing circuits. Although this arrangement is most desirable, the antenna may nevertheless be coupled to only one of said wing circuits. It will be understood that in the arrangement illustrated the coils 26 and 27 are usually and most desirably so wound and connected in the circuit that they are mutually assisting.

Particularly in the type of system illustrated, wherein the wing circuits are also free of iron cores and possess a low oscillation decrement, only a single wing circuit may be used.

Suitable means are provided to govern the frequency of the grid potential alternations. In the arrangement illustrated in Fig. 1, the tuned antenna circuit is utilized as the frequency governing or steering circuit. This is accomplished by including in the antenna circuit a winding 30, which is inductively related to the winding 23 connected to the grids 20 and 21, and thereby loosely couples the antenna and grid circuits. As here shown, the antenna circuit also contains a variable tuning inductance 31 by means of which the constants of the antenna circuit may be altered as desired to provide for transmitting at different wave lengths, for example. It is especially to be noted that the antenna circuit in this instance contains no iron core or repeater, and that it has a small oscillation decrement of the character previously described. The arrangement illustrated, wherein the inductances 30 and 31 are between coupling inductances 26, 27, and ground, with inductance 30 nearest ground, offers special advantages, and is preferred.

The operation of the system shown in Fig. 1 is briefly as follows: Direct current being supplied to the two wing circuits X and Y by the source of direct current B, pulsating currents are set up in the wing circuits by virtue of the circuit characteristics; and alternating current oscillations are induced in the antenna circuit. These latter immediately exercise a predominating influence, through the loose coupling 30, 23, on the grid potential alternations, each grid having impressed upon it potentials alternating in synchronism with the antenna oscillations but substantially out of phase with each other. The frequency of the antenna oscillations can be adjusted at will by shifting switch device 32, for example, to vary the effective value of inductance 31. It will be observed that simply by shifting a single controlling member, switch arm 32 in this instance, the frequency of the oscillations in the antenna or output circuit may be changed to any desired value without adjusting any other part of the system. The im-

portance of this arrangement in enabling, for example, rapid and easy shift to any desired wave length in transmitting radio signals is at once apparent.

- 5 In the arrangement shown in Fig. 2, an auxiliary frequency-controlling or steering circuit is employed to impress a governing alternating potential of the desired frequency on the connected grids. This auxiliary circuit may take various forms, but in any case must be capable of sharp tuning. As here shown it comprises a variable capacity 33, and inductance of which a part, 34, cooperates with winding 23 to loosely couple the grid and steering circuits; while pick-up coils 34^a and 34^b, cooperating with windings 28 and 29, respectively, loosely couple the steering and the output or antenna circuits. The antenna circuit may include a variable tuning capacity 35.

This embodiment of the invention operates in substantially the same manner as the system of Fig. 1, but the auxiliary tuned circuit governs the output frequency, taking energy from the wing circuits and impressing upon the grids an alternating potential of predetermined frequency.

Although a tuned antenna is shown in Fig. 2, the use of a special auxiliary steering circuit is not to be understood as limited to a system where the output circuit is tuned. On the contrary, an auxiliary, steering circuit is especially useful where it is not desired to have the output or consumption circuit tuned, or where the consumption circuit can not be as sharply tuned as the auxiliary steering circuit.

While the above described systems, which may be called "splitters", involve the use of more than one audion or equivalent device, certain features of the invention are evidently applicable to splitter systems in which only one of the parallel circuits contains such device, the other circuit being in the nature of a "by-pass" and containing inductance and capacity, for example. It is also to be understood that the systems herein disclosed may, within the invention, be inductively or otherwise associated with telephone or other input circuits, provided the steering or frequency-controlling circuit be capable of sharp tuning, as hereinbefore set forth.

What I claim is:

- 55 1. A system for generating alternating current comprising the combination with a source of direct current, of a pair of thermionic devices each including an anode, a cathode, and a modulating device cooperating therewith, parallel circuit connections whereby said thermionic devices are connected in circuit with said source and in parallel with each other, each of said parallel circuit connections including an inductive winding, a connection between said modulat-

ing devices, and a sharply tunable circuit inductively coupled to such modulating device connection in such manner as to produce alternating potentials of substantially differing phase on said modulator devices, said sharply tunable circuit including separate inductive windings cooperating respectively with the inductive windings in said parallel circuit connections. 70

2. In a system for generating alternating current, the combination with a circuit having a plurality of parallel branches, and means for energizing said circuit, of a plurality of thermionic devices, each including an anode, a cathode and a modulating device, each thermionic device having its anode and cathode included in its respective parallel branch of the circuit, whereby the thermionic devices are arranged in parallel with each other, a plurality of inductive windings, arranged one in each parallel branch of the circuit, a connection between said modulating devices, and a separate sharply tunable circuit coupled inductively, only, to such modulating device connection in such manner as to produce alternating potentials of substantially differing phase on said modulating devices, said sharply tunable circuit including separate inductive windings cooperating with the respective inductive windings in said parallel branches. 75 80 85

3. In a system for generating alternating current, the combination with a circuit having a plurality of parallel branches, and means for energizing said circuit, of thermionic means having anode, cathode and modulating means included in each of the parallel branches of said circuit, whereby parallel thermionic current paths are provided, a plurality of inductive windings, arranged one in each parallel branch of the circuit, a connection between the different portions of said modulating means in said parallel branches, and a separate sharply tunable circuit coupled inductively, only, to such modulating means connection in such manner as to produce alternating potentials of substantially differing phase on said different portions of said modulating means, said sharply tunable circuit including separate inductive windings cooperating with the respective inductive windings in said parallel branches. 90 95 100 105 110 115

4. In a system for generating alternating current, the combination with a circuit having a plurality of parallel branches, and means for energizing said circuits, of a plurality of thermionic devices, each including an anode, a cathode and a modulating device, each thermionic device having its anode and cathode included in its respective parallel branch of the circuit, whereby the thermionic devices are arranged in parallel with each other, a plurality of inductive windings, arranged one in each parallel branch 120 125 130

of the circuit, a connection between said modulating device, a separate circuit coupled inductively, only, to such modulating device connection in such manner as to produce alternating potentials of substantially differing phase on said modulating devices, said separate circuit including separate in-

ductive windings cooperating with the respective inductive windings in said parallel branches, and an output circuit related to 10 said parallel branches.

In testimony whereof I hereunto affix my signature.

FRITZ LOWENSTEIN.
